US0D1020531S

(12) **United States Design Patent** (10) **Patent No.:** **US D1,020,531 S**
(45) **Date of Patent:** **** Apr. 2, 2024**

(54) **TABLE ORNAMENT**

(71) Applicant: **Zejian Cai**, Guangdong (CN)

(72) Inventor: **Zejian Cai**, Guangdong (CN)

(**) Term: **15 Years**

(21) Appl. No.: **29/903,008**

(22) Filed: **Sep. 19, 2023**

(51) LOC (14) Cl. **11-02**

(52) U.S. Cl.

USPC **D11/157**; D21/496
